UNITED STATES PATENT OFFICE

2,010,236

WELL DRILL BIT

Richard F. Johnson, San Antonio, Tex.

Application March 8, 1934, Serial No. 714,574

6 Claims. (Cl. 255—61)

This invention relates to new and useful improvements in well drill bits.

One object of the invention is to provide an improved drill bit of the detachable cutter type.

5 A particular object of the invention is to provide an improved drill bit having a cutter fastening entirely housed in the head or body, whereby the cutter is more securely fastened and so long as the head remains connected to the drill stem 10 the fastening cannot become disengaged from the cutter.

A further object of the invention is to provide an improved cutter blade fastening which will be self-tightening.

15 Another object of the invention is to provide an improved drill bit comprising a body or head having a socket in its upper end receiving the cutter shank and a fastening in said socket engaging the shank and confined by the drill stem 20 or pipe connection which is engaged in said socket, whereby said fastening can only be disengaged by first removing the drill stem or pipe connection from the socket.

25 Still another object of the invention is to provide a drill bit in which short fluid ducts are provided and which deliver fluid close to the cutting edge of the blade; and also wherein the cutter fastener is sealed off from the fluids flowing through the body.

30 A construction designed to carry out the invention will be hereinafter described, together with other features of the invention.

The invention will be more readily understood from a reading of the following specification and 35 by reference to the accompanying drawing in which an example of the invention is shown, and wherein:

Figure 1 is a view partly in elevation and partly in vertical section, showing a drill bit constructed in accordance with the invention.

40 Figure 2 is a transverse vertical sectional view of the same.

Figure 3 is a plan view, the sealing disk and key being omitted.

45 Figure 4 is a plan view of the sealing disk.

Figure 5 is an enlarged side elevation of the key, and

Figure 6 is an elevation of the same.

In the drawing the numeral 10 designates a 50 head or body which may have any suitable shape, but which is preferably cylindrical at its upper end and wedge-shaped toward its lower end. An elongated transverse opening 11 is provided in the lower end of the head and an upwardly converging slot 12 extends from said opening. The

end and side walls of the slot are inclined toward the center of the head. The sides of the opening 11 are given the same inclination as the slot. An internally screwthreaded pin socket 13 is formed in the upper end of the head.

5 A cutter blade 14 is provided with a wedge-shaped shank 15 having a snug sliding fit upwardly in the opening 11 and slot 12. The blade has oppositely curved cutters 16 contiguous to the lower end of the head. The blade also has shoulders 17 at each side engaging in sockets 18 at each end of the opening 11, whereby the blade is braced against torsional strains and is less likely to be twisted from its shank 15.

10 At the bottom of the socket 13 a curved seat or sump 19 is provided at substantially right angles to the shank which has a rectangular opening 20 registering with said seat. A curved or crescent-shaped key 21 fits in said seat and passes through the opening 20 for fastening the blade in 15 the head. The key has a flat head 22 and a blunt point 23, being gradually reduced from its head to its point.

15 The top of the opening 20 is transversely rounded so that the key may be more readily 25 driven to draw the shank 15 into the slot 12. It is obvious that the curved seat will guide the key into the opening 20 and it is only necessary to start the point downwardly and slide the key into place. The curvatures will assist in positioning 30 the key and it is only necessary to tap the head 22 to tightly fasten the parts. Owing to the converging shape of the shank 15 and the curvature of the seat 19 it will be seen that as the shank 15 is driven up into the socket by the imposed 35 weight, when the cutters are on bottom, said key will slide in its seat into more intimate engagement with the shank, thus being self-tightening.

40 A sealing disk 24 fits in the bottom of the socket 13 so as to seal off the seat 19. The disk has nipples 25 extending therethrough and telescoping 45 the upper ends of fluid ducts 26 extending from the bottom of the socket on each side of the seat to the lower edge of the head on each side of the opening 11. The disk is provided with an eye 27 which may be engaged to lift it from the socket.

45 The disk seals off the seat 19 from the fluids delivered to the socket from the pin of the drill stem (not shown). These fluids are conducted 50 through the nipples 25 to the ducts 26. The disk also holds the key 21 in the seat. The short ducts 26 are important and their delivery of the fluids at the cutters is an advantage over those which discharge higher up the blade. The closer to 55

the cutters the discharge, the more effective is the washing.

It is obvious that so long as the seat 19 is sealed off by the disk 24, the key 21 cannot be disengaged from the shank 15 and the key being entirely housed within the head is protected and held in place. It would be possible to omit the disk and have the pin hold the key in the seat. The key is easily installed or removed, but cannot be lost in the well. The particular construction of the cutter blade is unimportant and may be changed for different kinds of drilling.

The description which has been given recites more or less detail of a particular embodiment of the invention, which is set forth as new and useful; however, I desire it understood that the invention is not limited to such exact details of construction, because it is manifest that changes and modifications may be made, within the scope of the appended claims, without departing from the spirit of the invention.

What I claim and desire to secure by Letters Patent, is:

1. A well drilling bit comprising, a body having a socket therein, a seat at the bottom of the socket, a cutter having its shank extending to said seat, a key mounted in said seat and engaging said shank, and a sealing member covering the seat and key at the bottom of the socket.
2. A well drilling bit comprising, a body having a socket in its upper end and an opening extending axially of the body up to the socket, a cutter having its shank engaging in said body opening, a fastening inserted through said socket and engaging said shank to hold said shank in the body, the body having ducts extending from the socket downwardly to the cutter, and a sealing member at the bottom of said socket covering

the fastening and having openings registering with said ducts.

3. A well drilling bit comprising, a body having a socket in its upper end and an opening extending axially of the body up to the socket, a cutter having its shank engaging in said body opening, a transversely covered seat at the bottom of the socket intersected by the shank, and a curved key mounted in said seat and passing through said shank. 5

4. A well drilling bit comprising, a body having a socket in its upper end and an opening extending axially of the body up to the socket, a cutter having its shank engaging in said body opening, a transversely covered seat at the bottom of the 15 socket intersected by the shank, a curved key mounted in said seat and passing through said shank, and a disk at the bottom of the socket covering the seat and key. 10

5. A well drilling bit comprising, a head having a screw-threaded pipe socket in its upper end, a cutter mounted at the lower end of the head and having its shank rigidly housed in the head and exposed to the socket, a fastening insertable only through the socket and engaging said cutter 25 shank for rigidly fastening said shank in said head, and a sealing member at the bottom of said socket covering the cutter shank and the fastening. 20

6. A well drilling bit comprising, a head having a screw-threaded pipe socket in its upper end, a transverse seat at the bottom of the socket, a cutter at the bottom of the head, a shank rigid in the head extending from the cutter through said seat, and a transverse key insertable through 35 said socket into said seat and engaging said shank for fastening it in said head. 30
